BIRD FEEDER

Frederick A. Nudd, 206 Lanson Road,
Ontario, N.Y. 14519

Filed May 19, 1972, Ser. No. 255,312

Term of patent 14 years

Int. Cl. D30—03

U.S. Cl. D30—13

FIG. 1

FIG. 2

FIG. 3

FIG. 4

FIG. 5

FIG. 1 is a front elevational view of a bird feeder, showing my new design;

FIG. 2 is a right side elevational view, the left side being substantially a mirror image thereof;

FIG. 3 is a top plan view;

FIG. 4 is a rear elevational view; and

FIG. 5 is a bottom plan view.

The diagonal lining in FIG. 2 indicates transparency.

I claim:

The ornamental design for a bird feeder, substantially as shown and described.
